UNITED STATES PATENT OFFICE.

EMERSON B. BIRD, OF SEATTLE, WASHINGTON.

JACK.

1,344,575.

Specification of Letters Patent. Patented June 22, 1920.

Application filed September 26, 1919. Serial No. 326,462.

To all whom it may concern:

Be it known that I, EMERSON B. BIRD, citizen of the United States, residing at 1608 Terry avenue, Seattle, in the county of 5 King and State of Washington, have invented certain new and useful Improvements in Jacks; and I do hereby declare the following to be a full, clear, and exact description of the invention, such as will enable others skilled in the art to which it 10 appertains to make and use the same.

This invention relates to jacks and more particularly to jacks for automobiles although it is not limited thereto.

15 An object of this invention is to provide a jack of simplified construction and of easy manual operation and a jack in which the reactionary forces are minimized as tending to force the pawl mechanism in causing it to 20 become disengaged under minimum resistance of the hand controlling operating means.

A further object of this invention is to 25 provide a unitary member for serving for varied purposes in jacking varied objects and having reduced stress action upon its engaging portions in its operation.

30 A further object of this invention is to provide an improved jack of the type in which the handle is lifted in releasing the pawl and in which the reverse motion is quickly and simply accomplished by reversing the movement of the handle.

With these and other objects in view, the 35 invention consists of the construction, combination and the detail and arrangement of parts as hereinafter more fully described and claimed.

In the drawings:

40 Figure 1 is a side elevation of this jack.

Fig. 2 is a construction in part at 2—2 of Fig. 1.

Fig. 3 is a detail of the standard.

Fig. 4 is a detail of the ball bearing 45 mount.

Fig. 5 is a detail of the upper ball race at 2—2 in Fig. 1.

Fig. 6 is a detail of the collar guarding the lever support.

50 Fig. 7 is a modified form of this device.

In detail the invention comprises a cylindrical unitary sleeve support 2 being screw threaded in its interior to mate with the screw threads 3 in a spindle 4, the said 55 spindle 4 being mounted and having a bearing in the standard 5, and a thrust ball

bearing 6 (Figs. 4 and 5) to receive the weight upon the said jack, and having a collar 7 serving as a bearing for a lever 8, the said lever 8 having pivoted thereon a 60 bifurcated pawl 9, and the said pawl 9 having a V shaped projection 10 for engaging a counter V shaped projection 11. The pawl 9 is adapted to engage the teeth of a ratchet 12 fixedly mounted on the spindle 4. 65 A handle 13 is pivoted to the lever 8 at 14 to move in a vertical plane and provided with an abutment member 15 which operates the V shaped member 11 yieldingly against a spring 16 so that when the handle 13 is in horizontal relation the V shaped member 11 engages the V shaped projection 10 in pawl 9 and causes the pawl 9 to engage the geared teeth 12 in the direction in which the handle is being turned. When 70 the handle 13 is lifted the V shaped member 11 is released from abutment 15 and forced backward by the spring 16 out of engagement with the projection 10 of pawl 9, thus releasing pawl 9 from engagement with the 80 teeth of gear 12 and admitting of a backward or other desired movement of the said handle without the engagement of the pawl with the said teeth.

In the modification shown in Fig. 7, the 85 hinged lever 13 is provided with an offset pawl 9 adapted to directly engage the gear 12.

What I claim is:

1. In a jack, the combination of a base 90 having a vertical bore, a spindle rotatably mounted in said base, a thrust bearing between said spindle and base, a sleeve adapted to be mounted on said spindle, said spindle and sleeve having co-mating threads, 95 and means mounted on said spindle between said base and said sleeve to rotate said spindle, said rotating means comprising a ratchet attached to said spindle, a collar rotatably mounted on said spindle above said ratchet, a hinged lever having one end mounted on said collar, a double acting pawl pivoted to said lever, and a sliding element carried by said lever and operated by the hinging thereof on its pivot for throwing said pawl.

2. In a jack having a base, a partially threaded spindle and co-mating threaded sleeve, a spindle operating device comprising in combination a ratchet, a hinged lever 110 rotatably carried on the spindle, a double acting pawl carried by said lever and adapt-

- ed to engage said ratchet, and a reciprocating spring controlled element adapted to control said pawl and to be operated by the hinging of said lever.
- 5 3. In a jack having a threaded spindle means for rotating said spindle comprising in combination a ratchet fixed to said spindle, a member rotatably mounted on said spindle adjacent to said ratchet, a double 10 acting pawl carried by said rotatable member, adapted to engage said ratchet, a slide- able member carried by said rotatable mem-

ber adapted to engage said pawl, but normally withdrawn from engagement therewith by a spring, and means for throwing 15 said sliding element into engagement with said pawl and at the same time to operate said pawl comprising a lever pivoted to said rotatable member and having an offset shoulder adapted to engage said sliding 20 member substantially as specified.

In testimony whereof I affix my signature.

EMERSON B. BIRD.
